UNITED STATES PATENT OFFICE

JULIUS SILBERGER, OF CLEVELAND, OHIO

DRILL

Application filed March 15, 1928. Serial No. 261,772.

This invention comprehends the use of air in digging or drilling mechanism for the purpose of conveying the dug material, which is in a partially comminuted state, the last 5 named condition being caused partly by the drilling apparatus itself, and partly by the action of the air on the loosened ground.

In carrying out my invention in actual practice, I avail of a casing that is hollow 10 throughout and has affixed at one end thereto appropriate digging instrumentalities, which are primarily designed to cut earth, either hard or otherwise, and pass the loosened earth back into the casing. Extending throughout 15 the casing is a tube of comparatively small diameter as compared with the bore of the casing, which functions as a conduit for a pressure fluid, such as compressed air. Openings in the tube aforesaid, adjacent to the 20 digging instrumentalities, permit the fluid to intermingle with the dug material and, under pressure, force the same back up and out of the casing in the space between the walls thereof and the walls of the tube.

25 A particularly noteworthy feature of novelty resides in the construction of the casing at the digging end. In a preferred form I have notched the end of the casing to provide what are in effect radial cutting 30 edges thereon, which, upon operative rotation of the casing, function as part of the digging instrumentalities. Other such members are radial knife blades enclosed by the 35 walls of the casing at the notched portion thereof, and a screw member which is adapted to taking a holding in the earth or substance upon which the mechanism is intended to operate.

40 Another praiseworthy feature of a drill provided by my invention is its adaptability for operations upon soils of widely varying character. The screw member aforesaid, is capable of digging in and obtaining a footing in even the hardest shales, and the digging 45 instrumentalities are particularly designed to effectively operate under such unfavorable conditions.

50 A more detailed feature of novelty lies in the arrangement of the holes provided in the fluid tube interiorly of the casing. These

openings are inclined upwardly, so that fluid passing therethrough will have assumed a direction, a component of which is the direction in which the materials are carried back by the said fluid.

55 Further, and more detailed objects and advantages will in part become apparent, and in part be hereinafter stated as the description of the invention proceeds.

For a full and more complete understanding of my novel idea, reference may be had to the following description and accompanying drawings in which,

60 Figure 1 is a view in side elevation of the working end of a drill made in accordance 65 with this invention.

Figure 2 is a longitudinal section through the drill taken about on the line 2—2 of Figure 1.

70 Figure 3 is a plan view from the bottom, bringing out particularly the arrangement of the digging and cutting instrumentalities.

Figure 4 is a showing in perspective of a 75 position of the digging means, and

Figure 5 is a detailed view in perspective of one of the radial cutting blades.

80 While a preferred specific embodiment of the invention is herein set forth, it is to be understood that I am not to be limited to the exact constructions illustrated and described, because various modifications of these details may be provided in putting the invention into practice within the purview of the appended claims.

85 The working end of a drilling or digging mechanism provided by this invention, is shown in Figures 1 and 2, and comprises a hollow, cylindrical casing A, having a bore extending throughout its length. Arranged preferably coaxial with the casing A, and interiorly thereof is a tube B, which has its extremity made fast to a portion of the digging instrumentalities indicated generally by the reference character C. These instrumentalities preferably include a stud 1, which plugs up the end of tube B, and is affixed thereto in any approved manner, such as by a screw threaded connection as shown at 2. The tube B may be held properly spaced 90 with respect to the walls of the casing A, by 95

the use of arms 3, having their walls affixed to the wall of the casing in any suitable manner, as by screws 4, which arms support a ring member 5, which surrounds the tube B. 5 Naturally, any suitable equivalent spacing medium may be substituted for that herein set out. The plug 1, has integral therewith, a tapered screw member 6, which functions as the holding or digging in means for the 10 cutting blades constituting the digging instrumentalities C. Intermediate the screw portions 6 and 2, this unitary structure has extending therefrom, cutting blades 7, which may be affixed thereto in any appropriate 15 manner, and which also have projections 8, that find suitable bearing in the walls of the casing A, as indicated at 9.

Referring now more particularly to Figure 1, it is noted that the extremity of the casing 20 A is notched, or serrated, as shown at 10, to provide cutting edges 11 that are radial in character. These cutting edges are adapted upon proper rotation of the casing 10, to operate on the substance on which the drill is 25 working, to cut and loosen the same. Needless to say, the cutting edges 11, and the blades 7, are disposed so that they both operate upon driving of the drill in one direction.

For a suitable distance above the digging 30 instrumentality C, the tube B is provided with openings 12, which are inclined slightly upward so that any fluid passing therethrough will have assumed a partial returning direction. The tube B is adapted to have fluid 35 under pressure, preferably compressed air, passed therethrough and out through openings 12 into the space between tube B and casing A.

Upon proper driving action being imparted 40 to the casing A, the digging instrumentalities C function to cut and loosen material, which is passed back into the casing A, where it has mingled with it the compressed air coming from the openings 12, which causes the material to assume a comminuted condition in 45 which it is passed up through the casing A, exterior of the tube B and delivered to any desired point.

Having thus described my invention, what 50 I claim as new, and desire to secure by Letters Patent of the United States is—

1. Drilling apparatus of the class described, comprising an outer casing, a fluid pressure tube axially disposed within said casing, said 55 tube having a plurality of rearwardly inclined passages adjacent to the forward end thereof, drilling instrumentalities carried by the end of said tube constituting a closure for said end, said drilling instrumentalities having a longitudinal passage therein and lateral 60 passages extending from said longitudinal passage in register with certain of the passages in the tube, said drilling instrumentalities constituting means for spacing the end 65 of the tube from the casing, and locking

means for retaining the registering passages in register.

2. Drilling apparatus of the class described comprising a casing, a fluid pressure tube axially disposed therein and having rearwardly inclined passages in the walls thereof adjacent to the forward end, digging instrumentalities positioned at the forward end of said casing, said digging instrumentalities comprising a stud removably carried by the end of said fluid pressure tube, a tapered feed screw formed on said stud and projecting beyond the casing, and radial cutting blades at the base of said feed screw, said blades constituting spacing means for the end 70 of the fluid pressure tube and means for positively interlocking the said digging instrumentalities to prevent shifting of the latter with respect to the casing and fluid pressure tube incident to operation of the same to remove material in advance of the said digging instrumentalities whereby to cause the said material to be subjected to the action of the fluid pressure to comminute the same and convey it rearwardly between the casing and fluid pressure tube.

In testimony whereof I affix my signature.

JULIUS SILBERGER.
